Primary Examiner — Richard Kearney

Assistant Examiner — Matthew Bird

(57) **CLAIM**

The ornamental design for a three-way shower diverter, as shown and described.

DESCRIPTION

FIG. 1 is a perspective view of a three-way shower diverter, showing our new design;

FIG. 2 is an enlarged perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines showing shower hardware in FIG. 1 depict environmental matter and form no part of the claimed design. The remaining broken lines depict portions of the three-way shower diverter that form no part of the claimed design.

1 Claim, 8 Drawing Sheets
